UNITED STATES PATENT OFFICE

JAMES M. WINTON, OF CLEVELAND, OHIO, ASSIGNOR TO THE WINTON ENGINE COMPANY, OF CLEVELAND, OHIO, A CORPORATION OF OHIO

AIR STARTER TIMING MEANS

Application filed February 10, 1928. Serial No. 253,395.

This invention relates to means for timing distributing means in a reversing internal combustion engine, and more particularly the invention has to do with means for automatically properly timing the distributing valve of an air starting system for a multiple cylinder internal combustion engine provided with the usual double set of cams upon a cam shaft slidable to bring the selected set of cams into operative position to actuate the engine exhaust and inlet valves to run the engine in the corresponding selected direction.

Besides properly presetting the valve actuating means, the engine must be started, and for this purpose it is customary in said types of engines to provide air starting means.

This air starting means ordinarily comprises a system including a source of compressed air supply, communication with the several combustion chambers of the engine, and a distributing valve between the air supply and the combustion chambers whereby air is admitted to the several chambers in proper order to start the engine rotating in the desired direction, the air of course being shut off as soon as the engine starts firing in this direction.

Where the engine is to be reversed it will be apparent that the timing of the distributing valve must be altered to admit air to the cylinders in sequence differing according to the desired rotational direction of the engine.

It is old in the art to employ a shiftable cam shaft to take care of the engine valve timing; and it is likewise old to provide means for shifting the starter distributing valve.

It is the object of my invention to associate the distributing valve with the cam shaft, to be driven thereby in either direction of running of the engine and further to be automatically shifted and timed dependent on the shifting and timing of the cam shaft.

An advantage of such arrangement lies in the result that a single operator operated control means may be provided, which may be the usual cam shaft shifting means, and movement of which between "forward" and "reverse" positions, will properly time both the engine valves and the starting means, for running the engine in the desired direction.

Further objects and advantages will be apparent from the following description taken in connection with the accompanying drawings in which Fig. 1 is a view in elevation and partly in section, showing pertinent parts of an engine to which my invention has been applied; Fig. 2 is an end view of the showing of Fig. 1; Fig. 3 is a section as in the plane of line 3—3, Fig. 1 and Fig. 4 is a section as in the plane of line 4—4, Fig. 1.

With reference now to the drawings 1 is a portion of the crank case of a six cylinder engine in which is fitted a babbitt-lined bushing 2, in which bears the cam shaft 3 of the engine.

Assuming the engine as operable on a four stroke cycle, and all of the engine valves actuated by the same cam shaft, the shaft 3 is provided with 12 double cams one, 4, being shown. The double cam 4 is actually a pair of cams 4^a and 4^b having therebetween a ramp portion 4^c, and the function of the cam 4 is to actuate one of the valves of the engine by raising at the proper time a tappet 5 slidable in the crank case, carrying a roller 6, and caused to bear against and follow the cam by the usual valve spring not shown, all of these parts being standard in the art.

Assuming the cam portion 4^a to be the "forward" cam, in the position of the parts shown, the valve actuated by the tappet 5 will be actuated in proper timed relation to run the engine in the forward direction; and when the cam shaft 3 is shifted to the left Fig. 1 until the roller 6 rests upon the cam portion 4^b the engine will be operating in the reverse direction. By the provision of the ramp portion 4^c the cam shaft may be shifted to bring either of the cam portions 4^a or 4^b under the roller regardless of the angular position of the cam shaft in its bearings.

For starting the engine a compressed air system is provided and includes a distributor block 7 secured with the engine crank case 1 opposite the end of shaft 3, a cap 8 secured with the distributing block 7, and a distributing valve 9 having a stem portion 10.

The distributor block 7 carries a face plate 11 in which are ports 12, 12', etc., one for each cylinder of the engine and each communicat-

ing with its cylinder by a passage 13, 13', etc., in the distributor block 7, and piping 14, 14', etc. The cap 8 is recessed as at 15 to clear the distributing valve 9 and the recess 15 has communication subject to a suitable starting valve not shown, with a source of compressed air supply by way of the passage 16 and piping 17. A ball 18 is arranged to bear against the valve 9 by a spring 19 for the purpose of maintaining the valve 9 seated upon the plate 11. A lead 20 may be provided in the cap 8 for connection as at 21, with a pressure gauge.

The distributing valve 9 has a single port 22 properly positioned to uncover in sequence, as the valve is rotated, the several ports 12, 12', etc., the remaining ports 12', etc., being closed by the seating of the distributing valve upon the plate 11.

20 Since the engine operates on a four stroke cycle, the distributing valve 9 should rotate at half crank shaft speed; and since the cam shaft 3 rotates at half crank shaft speed it is convenient to drive the distributing valve from the cam shaft, and such arrangement is not new in the art.

According to my invention, however, I connect the distributing valve and cam shaft in such a manner that when the cam shaft is shifted longitudinally the distributing valve will have rotational movement with respect to the cam shaft to properly time the distributing valve dependent upon which of the cam portions 4^a or 4^b are brought to operative relation with the tappet 5.

For this purpose I provide on the stem 10 of the distributing valve helical grooves or threads 23 of the proper pitch to rotate the distributing valve through the necessary angle by reversing shifting movement of the cam shaft through the necessary longitudinal distance. The end of the shaft 3 is counter-bored to receive a shell 24 having a number of spaced openings 25 bevelled outwardly as indicated. Within the shell 24 and secured by lug portions fitting in the openings 25 is a nut 26 internally threaded to fit the stem 10 of the distributing valve. Preferably the threads 23 are unevenly spaced, as by omission 50 of one of an otherwise evenly spaced series, whereby the valve can only be fitted to the assembly in the proper relation.

The nut and shell assembly is conveniently effected by babbetting around the distributing valve stem, that is, by properly positioning the stem within the shell and pouring therebetween babbitt to form the nut. The nut and shell assembly is secured in the counter bore of the shaft by any convenient means 60 such as the pin 27, the assembly being of sufficient length that the pin will be cleared by the end of the valve stem.

Operation will be apparent. Assuming the parts in the position of Fig. 1, the "forward" position, to reverse the engine after

70 stopping the same it is merely necessary to shift the cam shaft 3 to the left until the cam portion 4^a is replaced by the cam portion 4^b; the nut 26 by such longitudinal movement rotating the distributing valve by cooperation of the thread therebetween to time the distributing valve in the reverse position. Thereafter admission of compressed air through the pipe 17 will start the engine in reverse motion.

75 Likewise return movement of the cam shaft to the position indicated will effect return of the distributing valve to its "forward" position. Of course shifting of the cam shaft may be accomplished and the described results effected regardless of the angular position of the cam shaft.

80 What I claim is:

1. In combination with a distributing valve 85 of the class described, driving and driven members for said valve and having concentrically arranged parts with helical interengaging elements whereby sliding movement of one of said members will change the timing of said valve, said parts being of unsymmetrical section whereby their interengagement 90 may be effected only in one angular relation at the section.

2. In combination with a distributing valve 95 of the class described, concentrically arranged driving and driven members for said valve with helical interengaging elements whereby sliding movement of one of said members will change the timing of said valve, the inner of 100 said members being of hard metal, and the outer of said members comprising a hard metal shell with a soft metal liner therefor.

In testimony whereof I hereby affix my signature.

JAMES M. WINTON.
